(57) **CLAIM**

The ornamental design for a hanger, as shown and described.

DESCRIPTION

The present application is related to pending U.S. patent application Ser. No. 12/480,994, entitled "Hanging Display Package and Associated Products and Methods," filed on Jun. 9, 2009.

FIG. 1 is a front, perspective view of a hanger showing a first embodiment of our new design;

FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front, perspective view of a hanger showing a second embodiment of our new design;

FIG. 10 is a rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is bottom view thereof.

It is understood that the invention disclosed in FIGS. 9-16 disclose undetermined overall relative dimensions of the hanger with the basic configuration being the same as that of the first embodiment in FIGS. 1-8. The broken lines are for illustrative purpose only and form no part of the claimed design.
